UNITED STATES PATENT OFFICE

CHARLES A. FRENCH, OF COLUMBUS, OHIO, ASSIGNOR TO FARMERS NATIONAL BANK,
OF GREENVILLE, OHIO, A CORPORATION OF OHIO, TRUSTEE

STEAM POWER PLANT

Application filed May 26, 1923. Serial No. 641,737.

This invention relates to steam power plants and particularly to improvements in automotive steam power plants of the type shown in my co-pending application Serial 5 Number 592,695.

In the application above referred to, I have pointed out the difficulties heretofore encountered in automotive steam power plants and the necessity for reliable automatic control of the quantity of water (liquid and steam) in active circulation in the system, and disclosed a closed system in which a fixed quantity of water is circulated continuously provided with automatic means for "making up" of the slight quantity of water that is unavoidably lost by leakage.

The present invention relates to the same type of power plant and provides a thermostatically actuated valve, the operation of which is controlled by the amount of water in the system, for directly controlling the admission of "make up" water.

Referring to the drawings—

Fig. 1 is a diagrammatic representation of 25 a steam power plant embodying my improvements;

Fig. 2 is an enlarged view of the thermostatic valve; and

Figs. 3 and 4 are similar views of a modified 30 construction.

Exhaust steam from the pipe 10 enters the condenser 11, from which the condensed water is withdrawn through pipe 12 by a pump 13 (preferably of the rotary type) and discharged through pipe 14 into the hot well 35 and skimmer 15 from which the air escapes through vents 16 and the excess of oil is drawn off through the overflow pipe 17, while the water rises between the baffles 18, 19 and over- 40 flows into chamber 20 of the hot well, from where it enters the intake pipe 21 of the feed pump 22. The pump has intake and discharge valves 23 and 24, the intake valve normally closing on the discharge stroke of the 45 pump, but being held open by a push rod 25 when the head of water in the hot well and intake pipe 21 is insufficient to hold the diaphragm 26 depressed against the pressure of the spring 27, so that the pump will not discharge water to the boiler but will return it 50

to the intake pipe, thereby preventing all the water from being withdrawn from the hot well and the pump's becoming air bound. When there is sufficient water in the hot well to depress the diaphragm 26, the pump discharges through the pipe 28 to the boiler. The boiler comprises a preheater 29, evaporator 30, and superheater 31 enclosed within a shell 32 to which heat is supplied from a burner 33, the hot gases flowing downward and radially outward through the boiler and being discharged downward through the annular flue 34.

As shown in the drawing, the preheater, evaporator and superheater are formed from a plurality of concentric banks of coils, the water from the feed pump entering the outer coil of the preheater in the coolest part of the boiler and advancing progressively through the coils toward the center or hottest part of the boiler. Hot water from the preheater enters the outer evaporator coil through an ejector 35 where it picks up additional water from the storage drum 36. Wet steam or a mixture of steam and water from the evaporator 30 is discharged tangentially into the storage drum from pipe 37, the water separated by centrifugal action accumulating in the drum while the dry steam is taken from the top of the drum by the dry steam pipe 38 leading to the superheater 31. Steam from the superheater leaves the boiler through the steam main 39 leading to the main engine or other prime mover and the auxiliary engine 44.

The water accumulating in the storage drum is returned to the evaporator through the pipe 40 and ejector 35 as previously described. An auxiliary circulating pump 41 is operated by shock from the feed pump 22 and is connected in the pipe 40 to assist in the circulation through the evaporator. A free piston or plunger 42 in this pump is moved in one direction or on its discharge stroke by shock from the feed pump with the delivery side of which it is in direct communication. The plunger is moved in the opposite direction or on its intake stroke by a spring 43 during the interval that the pump 22 is making its intake stroke. It will be understood that

the pump 41 and ejector 35 mutually cooperate to produce the same result and that either may be used without the other in many instances.

- 5 An auxiliary engine 44, which is preferably operated by steam from the boiler, drives the pumps 13 and 22 and also an auxiliary feed pump 45 which normally draws in water from a reservoir 46 and returns it thereto through 10 pipe 47, 48, valve 49, and pipe 50. The valve 49 is normally open so that the pump 45 merely circulates water through the parts just described, but if the amount of water in circulation through the system falls below 15 normal, the valve 49 is closed by thermostatic means and the pump 45 then discharges through the check valve 51 into the feed pipe 28 until the quantity of water in the system is restored to normal.
- 20 The valve 49 is connected to the expanding element 52 of a thermostat mounted on the storage drum 36. The expansion element is hollow and its lower end is rigidly connected at 53 to the drum below the normal water 25 level while its upper end is connected by a tube 54 to the drum above the normal water level, the tube 54 being sufficiently flexible to permit expansion of the thermostat. The 30 valve and movable end of the expansion element are guided by rods 55, 56 carrying springs 57, 58 against the pressure of which the valve may move if the expansion element continues to expand after the valve is closed, as is clearly shown in Fig. 2.
- 35 When the system is operating under normal conditions and the pump 22 is returning water to the boiler as fast as steam is being generated, the level of the water in the storage drum is high enough to cover the expansion 40 element and the valve 49 is held open. But if the supply of water fails or the amount in circulation decreases through leakage or for any reason, the level in the drum will fall exposing the expansion element to the steam so 45 that it expands and closes the valve 49. The auxiliary pump then delivers water to the boiler until the level in the drum is restored, after which the thermostat contracts and opens the valve 49.
- 50 In Figs. 3 and 4 I have shown a modified form of my invention in which the auxiliary feed pump is dispensed with and the "make-up" water is supplied to the hot well, the 55 valve controlling the supply of "make-up" water being closed normally. In these figures, many of the parts are the same as in Figs. 1 and 2 and therefore are designated by the same reference characters and will not be described in detail.
- 60 The reservoir 60 contains a supply of "make-up" water and is connected by a pipe 61 to the valve 62 which is normally held seated by contraction of the expansion element of the thermostat. A pipe 63 leads from the 65 valve to the hot well 15. The head 64 of the

valve is connected to the free end of the expansion element 65, the fixed end of the expansion element being mounted in the frame 66 by which it is connected through the nipple 67 to the drum 36 below the normal water line. The valve and movable end of the expansion element are supported on the guides 68, 69 which carry springs 69, 70 offering a yieldable resistance to movement of the valve caused by further contraction of the thermostat after the valve is closed. The upper end of the thermostat is connected by a slightly yieldable tube 71 to the drum above the water line.

When the system contains the normal 80 amount of water in circulation by the feed pump, the level in the drum 36 will be high enough to cover the thermostat, which will be relatively cool, as the water is not in circulation, and hold the valve 64 seated so that no 85 water will flow from the reservoir 60 to the hot well. But, when for any reason the water level in the drum falls, the expansion element will be subjected to the temperature of the steam and, expanding, will open the 90 valve 62 so that water will flow to the hot well until normal operating conditions are restored.

The power plant just described is of the closed type, in which a relatively fixed quantity of water is being continuously circulated, only enough "make-up" water being added from time to time to replace unavoidable losses. The water is supplied to the boiler by the feed pump 22 which is driven at 100 constant speed from the auxiliary engine and is of sufficient capacity to take care of the maximum load on the boiler. The burner 33 is of the hit and miss type, that is, it is either burning at full capacity or entirely 105 shut off, there being no intermediate stages or rates of burning. The size of the burner and rate of circulation through the coils are such that when the burner is fully on, and the boiler carrying its maximum load, steam 110 will be generated at 500 pounds pressure per square inch and 300 to 400 degrees superheat. Since all of the steam is condensed and returned to the hot well, the pump 22 supplies the maximum amount of water when the steam consumption is a maximum and supplies the minimum amount of water when the steam consumption is a minimum, and for all intermediate loads the amount of water pumped is proportional thereto. However, if the water in the hot well reaches a certain low level the pump will miss until the water raises sufficiently in the hot well. The amount of water going through the preheater coils 29 is therefore always equal to the 115 amount of steam being generated. The water coming from the preheater through the ejector induces a quantity of water from the storage drum which, together with the water from the impulse pump (if used) is about 120 125 130

three times the amount of water evaporated. The pipe 37 therefore discharges a mixture into the drum of 25 to 30 per cent steam and 70 to 75 per cent water. A supply of water is always assured in the drum and the circulation through the coils is at a very high velocity because of the amount of water handled, and increases with the rate of steaming. I have discovered that the amount of steam generated or the amount of heat absorbed in the coils increases with the velocity of the fluid in the coils, therefore by circulating three to four times the amount of water through the evaporator required for steam, the velocity is increased and the steam generated greater than it would be if the velocity were less. Since the velocity increases in direct ratio with the amount of steam demanded, the boiler is most efficient at its maximum load. When the power plant is operating under light loads, the pump 22 will not deliver water to the preheater at every stroke because the amount of water being returned to the hot well from the condenser is small. The rapidity of circulation in the preheater will therefore fall off and the amount of water picked up from the drum by the ejector will decrease. The rapidity of circulation in the preheater will therefore fall off and as the fire will only be burning for a small portion of the time the evaporating coils will fill by gravity from the drum when the fire is not burning. When the demand for steam is small, naturally vaporization of a very small quantity of water in the evaporating coil will suffice to restore the pressure to normal. When the demand for steam is small it is not important that there should be a rapid circulation of water in the evaporating coils, as the fire can only be on a very short space of time, never in any case sufficient to produce superheat in these coils.

Having thus described my invention what I claim as new and desire to secure by Letters Patent is:

1. In a steam power plant, the combination of a boiler having a storage drum in which a reserve of hot water is maintained, a hot well, means for supplying water thereto, a pump controlled by the water level in the hot well for supplying water to the boiler and drum, and means controlled by the water level in the drum for supplying additional water to the boiler when the supply in the hot well fails.

2. In a steam power plant, the combination of a boiler, a condenser, a feed pump, control means whereby the pump supplies water from said condenser to the boiler at substantially the same rate that steam is being used, a water reservoir, a hot water storage drum, a conductor connecting the drum with the boiler and means controlled by the quantity of water in the drum to supply additional water to the boiler from said reservoir when

the quantity in the drum is less than a predetermined amount.

3. In a steam power plant of the type in which a quantity of water is continuously circulated and alternately vaporized and condensed, the combination of a boiler, a hot water storage drum, a conductor connecting the drum with the boiler, a feed water pump, means for returning water to the pump at substantially the same rate that steam is taken from the boiler and means controlled by the amount of water in the drum for delivering additional water to the boiler when the amount returned to the pump is less than the steam taken from the boiler.

Signed at Columbus, Ohio, this 24th day of May, 1923.

CHARLES A. FRENCH.
